UNITED STATES PATENT OFFICE

WILLIAM REX BELL, OF TERRE HAUTE, INDIANA

POSTER COPY CONDITIONING MACHINE

Application filed June 25, 1927. Serial No. 201,369.

This invention relates to a device for moistening display poster material.

The chief object of the invention is to moisten display poster material and remove from the same the creases and unevenness and substantially all stretch.

The chief feature of the invention consists in the provision of means for supplying a substantially uniform amount of water to a relatively absorbent poster medium, whereby the same will be moistened or tempered and remain so for a relatively long period of time without disintegration and will be so arranged that substantially all the stretch and creases will be removed therefrom.

The full nature of the invention will be understood from the accompanying drawings and the following description and claim:

In the drawings Fig. 1 is a top plan view of a moistening device embodying the invention. Fig. 2 is a side elevation thereof. Fig. 3 is a transverse sectional view taken on line 3—3 of Fig. 2, and Fig. 4 is an enlarged transverse sectional view of the poster roll mounting.

In the drawings 10 indicates a framework having suitable compartments 11 for reception of rolls of moistened paper posting copy, the same being wrapped in oil cloth or similar material so as to retain the moisture. A perforated support in the form of a screen or table top 12 is supported by the frame 10 and adjacent thereto is a U-shaped trough 13 in which is mounted an open bearing member 14 having the inclined slot 15 therein for receiving the end of the shaft 16. The other end of the shaft includes a universal joint 17 connected to a stub shaft 18 mounted in a bearing 19 supported by the frame 10. Shaft 18 is driven by a pulley 20 driven by a belt 21 connected to a driving pulley 22 driven by an electric motor 23 controlled by foot pedal 24 connected by link 25 to a control mechanism 26. The trough 13 is adapted to contain water or other moistening liquid and the material to be moistened is rolled under water and it has been determined that the tension in the roll obtained in rolling is sufficient to permit just sufficient

moisture to be retained by the material to be moistened.

In pasting posters the copy is usually supplied in standard dimension sheets or certain sizes and multiples thereof. These sheets are supplied folded and heretofore it has been the practice to unfold these sheets in the field adjacent the posting board and moisten them with paste after moistening the board with paste, and then mounting the several sheets on the board in proper relation to form the entire sign. The present invention contemplates unfolding of each sheet at the moistening plant so that all the wrinkles and creases and folds, as well as uneven stretching will be removed therefrom. After unfolding upon the perforated table or top 12, the bottom end of the sheet is passed into the trough and thence is wrapped around the shaft 16 and retained thereon by an elongated spring clip in the form of a partial cylinder 27, the copy sheet being represented by the numeral 28. As the shaft 16 is rotated, the copy is passed thru the tank, subjected to water and moistened to the desired degree when rolled upon the shaft. After the sheet has been entirely moistened and rolled the shaft 16 is removed thru the slot 15 from the bearing 14 and elevates sufficient to permit pulling of the copy from the shaft. The rolled copy is then enclosed in an oil cloth or similar wrapper or container and then taken to the field for posting. The paper so moistened has uniform stretch. All the wrinkles and creases are removed from it and the material remains in a moistened or tempered condition suitable for easy handling and will remain in said condition for at least a day and it has remained for several days. The resultant roll, therefore, is such that the outer end of the roll is positioned at the top of the sign board and the copy is paid out therefrom, the roll dropping by gravity and being pasted thereto without further manipulation other than the previous application of the adhesive to the board and brush pressure.

30 also indicates a similar framework supporting the motor 23 and including drawer receiving compartments 31, each being 100

adapted to receive the full copy for one or more signs. Supported by the frame 30 is the trough 32 within which is mounted a shaft 33 in a pair of open bearings 34. Mounted on the shaft 33 are the adjustable end plates 35 guiding a roll 36 of blanking paper. The roll revolves in the tank and the paper 37 passes upwardly over a friction and severing strip 38 which is relatively smooth and serves to scrape the surplus moisture from the paper 37 and such excess drips on to the drip plate 39 and is returned to the tank. The sheet 37 is rolled up upon shaft 40 mounted in an open bearing 41 at one end and having a universal connection 42 at the opposite end and the sheet is anchored to the joint in the same manner as shown in Fig. 3 and previously described. The shaft 40 is rotated by the stub shaft 43 to which it is connected by said universal shaft 42 and said stub shaft is rotated by the pulley 44 driven by belt 45 which is the same as belt 21, said belt passing once around the pulley 22.

25 A recording device 50 having an indicating arm 51 movable adjacent a scale 52 is associated with the shaft 40 so that the amount of blanking paper can be accurately determined in a roll and thus only sufficient paper 50 necessary for the board of work of each sign or display will be mounted in any one roll.

The foregoing device is of such a nature that the employment of the perforated top 33 permits the paper to be sprinkled when desired, the surplus dripping thru, and when the paper is passed thru or into the tank the surplus does not creep back along the table supporting the posting material and thus 40 unevenly moisten the unmoistened part of the poster. If the poster were unevenly moistened, uneven stretching or creasing would subsequently form by reason of uneven stretch in it.

45 Another advantage that the foregoing arrangement secures is that in rolling the material to be posted under water the tension in the roll is such that the surplus water is crowded from the roll and only sufficient water is retained therein to completely moisten the roll but not to over-moisten the same. Thus, the following resultant conditions do not obtain with the present device, towit, a roll having an exterior portion sufficiently moist with an interior insufficiently moist, or in interior sufficiently moist with an exterior excessively moistened so as to disintegrate the material when it is handled.

50 The present device secures the tempering of poster material with just sufficient amount of moisture requisite therefor, evenly distributed and at relatively great speed and with a low labor cost. The moistened poster material then is in such shape that it can be 55 mounted on the posting panels or boards

without creasing or wrinkling and without applying glue or paste to the printed face of the posting material such as heretofore has been required.

50 After the roll has been formed of moistened or tempered paper, the same is stripped from the shaft and even tho the paper be in a moistened condition the same when in rolled formation, has sufficient stability or rigidity so that it will not buckle in the roll and can be handled as if the interior were reinforced by the shaft or a supporting rod.

55 The invention claimed is:

20 In a poster copy conditioning machine the combination of a frame, a reticulated surface for sheet support, a tank, roll driving and supporting means therein, a roll support detachably associated with the driving and supporting means, a power means for rotating the driving and supporting means to roll the sheet while immersed in the tank.

25 In witness whereof, I have hereunto affixed my signature.

30 WILLIAM REX BELL.
